UNITED STATES PATENT OFFICE.

CHARLES ALTMAN, OF NEW YORK, N. Y.

FUR-SACK FASTENING.

SPECIFICATION forming part of Letters Patent No. 278,072, dated May 22, 1883.

Application filed March 30, 1883. (No model.)

To all whom it may concern:

Be it known that I, CHARLES ALTMAN, a citizen of the United States, residing at New York, in the county and State of New York, have invented new and useful Improvements 5 in Fur-Sack Fastenings, of which the following is a specification.

This invention relates to that class of fastenings composed of a flexible loop and a button, and is especially adapted to sacks made of seal-skin or other fur. Prior to my invention said loop has been attached to the face of the sack, near one edge of the sack-opening, to engage the button which is attached 10 to said face near the other edge of the opening. This arrangement, however, is objectionable, because when the loop is placed on the button it is liable to rub against and chafe or wear the fur on the outer edge of the sack-opening, due to the fact that the loop crosses said edge, and hence the sack is thereby rendered 15 unsightly in a comparatively short time. To overcome this disadvantage I arrange the loop on the back of the sack near the proper edge 20 of the sack-opening, and in proper relation to the button, as hereinafter more fully described, and as illustrated in the accompanying drawings, in which—

Figure 1 is a front view of a portion of a sack containing my fastening, the sack-opening being closed. Fig. 2 is a like view, showing the old arrangement of the loop. Fig. 3 is a like view, showing the sack-opening unfastened. Fig. 4 is a rear view of one edge of said 25 opening.

Similar letters indicate corresponding parts.

The letters A B designate the two edges of the sack-opening, and C D the loop and button composing the sack-fastening. When the 30 sack-opening is closed said edges A B overlap each other, and are held shut by the loop C when

the latter is placed on the button D, the loop and button being situated near the edges, in distinction from upon the edges, of the opening. By referring to Fig. 2, where the loop C is shown 45 as being on the face of the sack, it will be seen that the loop crosses the outer or exposed edge, A, of the sack-opening, and hence it is liable to rub against and chafe or wear the fur on said edge. In the example shown in 50 Figs. 1, 3, and 4 the loop is attached to the inner surface or back of the sack, adjacent to the edge A of the sack-opening, and at the proper place to engage the button D, which is attached to the face of the sack, near the 55 other edge, B, of said opening; and it will be readily seen that by this arrangement of the loop my fastening is left free of the objection above named. Said loop C is made of braid or other suitable material, and may be attached 60 to the sack by stitching s, or otherwise, while the button D is arranged in symmetrical position with a blind button, E, and suitable trimmings for imparting to my fastening an ornamental character.

What I claim as new, and desire to secure by Letters Patent, is—

The sack-fastening herein described, composed of the loop C, which is attached to the inner surface of the sack, near one of the 70 overlapping edges of the sack-opening, and of the button D, which is attached to the face of the sack, near the other edge of said opening, substantially as described, for the purpose set forth.

In testimony whereof I have hereunto set my hand and seal in the presence of two subscribing witnesses.

CHARLES ALTMAN. [L. S.]
